Patented Mar. 2, 1915.

2 SHEETS-SHEET 2.

UNITED STATES PATENT OFFICE.

THOMAS H. SHELDON, OF VICTOR, COLORADO, ASSIGNOR OF ONE-HALF TO FELIX HERZ,
OF GOLDFIELD, COLORADO.

AUTOMATIC BRAKE-SETTING AND SIGNAL-OPERATING APPARATUS FOR RAILWAY- TRAINS.

1,130,028.

Specification of Letters Patent.

Patented Mar. 2, 1915.

Application filed January 27, 1913. Serial No. 744,515.

To all whom it may concern:

Be it known that I, THOMAS H. SHELDON, a citizen of the United States, residing at Victor, in the county of Teller and State of Colorado, have invented certain new and useful Improvements in Automatic Brake-Setting and Signal-Operating Apparatus for Railway-Trains; and I do declare the following to be a full, clear, and exact description of the invention, such as will enable others skilled in the art to which it appertains to make and use the same.

This invention relates to improvements in automatic brake setting and signal operating apparatus for railway trains.

One object of the invention is to provide an apparatus of this character having means whereby the air is automatically released from the air brake mechanism of a train and the brakes thus automatically applied when the train reaches a signal set at danger thereby obviating any possibility of the train running past the signal in the event that the engineer fails to see the same.

Another object is to provide an automatic brake setting apparatus having means whereby signals are repeated or the conditions of the track indicated in the cab of the locomotive or motor car in plain sight and hearing of the engineer.

A further object is to provide an apparatus of this character which will be comparatively simple in construction, efficient and reliable in operation and which may be arranged for operating the brakes and displaying signals in trains going in either direction on single tracks.

With these and other objects in view, the invention consists of certain novel features of construction, and the combination and arrangement of parts as will be more fully described and claimed.

In the accompanying drawings: Figure 1 is a diagrammatic plan view of a section of a railway track and a semaphore signal showing one form of the apparatus and system of wiring; Fig. 2 is a longitudinal sectional view of the air releasing valve of the apparatus; Fig. 3 is a cross sectional view 50 of the valve taken on the line 3—3 of Fig. 2; Fig. 4 is a detail side view of one end of the contact rail and the contact shoe or member of the apparatus.

Referring more particularly to the draw-

ings, 1 denotes the track rails, 2 denotes the front axle having the usual track engaging wheels 3, and 4 denotes the rear axle having track engaging wheels 5. Arranged at a suitable position between the track rails 1 are third or contact rail sections 6 and 7 with which the contact shoes 8 and 9 carried by the locomotive or motor car are adapted to be engaged for taking the current from said contact rails when the latter are energized and to which are connected current conducting wires leading to the brake controlling mechanism of the apparatus as will be hereinafter described.

On the right hand side of the track is arranged a semaphore signal 10 which may be of the usual or any preferred construction and which in this instance is provided with a home or local signal arm 11 and a distant signal arm 12. The base 13 of the semaphore has arranged therein the battery 15 which is connected with one of the track rails 1 by a current conducting wire 16 and to the third rail section 6 by current conducting wires 17 and 18. The wire 17 forms a straight connection from the battery to the third rail while the wire 18 has therein a resistance coil 19 through which the current from the battery must pass before reaching the third rail 6 so that the current supplied to the rail through the coil 19 is considerably weaker than the current supplied through the straight connection 17.

In the current conducting wire 17 is arranged a switch or circuit closer 20 while in the wire 18 is arranged a circuit closer 21. The switches or circuit closers 20 and 21 are connected in any suitable manner with the signal arms 11 and 12 of the semaphore whereby when said arms are moved to positions indicating caution or danger, said switches or circuit closers will be closed thereby completing the circuit between the battery 15 and the third or contact rail, so that when a train reaches the signal and the contact shoes carried by the train are engaged with the energized rail the circuit connected with said shoes will be completed. The current of this circuit is employed for actuating the mechanism of the brake applying apparatus carried by the car as will be hereinafter more fully described.

Arranged in the cab of the locomotive or motor car is an electrically operated air re-

leasing valve 22 which is operated by the apparatus when the contact shoes carried by the locomotive come into contact with an energized third rail whereby the air is released from the train pipe and the air brakes of the entire train thus applied. The valve 22 comprises a main casing 23 having therein a main valve 24 for effecting the release of the air from the train pipe and a supplemental valve casing 25 having therein a valve 26 adapted to control the admission of compressed air to the main valve 24 whereby the latter is actuated for releasing the air of the train pipe. In the main valve 23 is an air inlet port 27 and an air discharge port 28. Formed on the valve casing and connecting with the air inlet port 27 is a threaded socket 29 adapted to receive the end of the pipe which connects the valve 23 with the train pipe. The valve 24 is preferably in the form of a spool valve and in its normal position is adapted to close the discharge port 28 thereby holding the air pressure in the train pipe. The valve 24 is provided with a stem 30 whereby the same may be manually set after being operated to release the air.

The supplemental valve casing 25 has in its upper portion series of air passages 31 the outer ends of which communicate with the adjacent end of the main valve casing to which the supplemental casing is attached. The inner ends of the passages 31 connect with an annular air discharge passage 32 which is normally closed by the valve 26. In the outer portion of the valve casing 25 is formed an air inlet passage 33 which communicates at its inner end with an annular air passage 34 arranged in and communicating with the valve casing between the heads of the valve 26 as shown. Connected with the valve casing 25 and communicating with the passage 33 is an air conducting pipe 35 the opposite end of which is connected with the socket 29 whereby the air from the train pipe is admitted to the valve casing 25 between the heads of the valve 26 therein. The valve 26 when in a normal position closes the air discharging passages 31 and 32 and thus prevents the air from entering the adjacent end of the main valve casing. As soon, however, as the supplemental air valve 26 is shifted the passage 32 will be uncovered thus permitting the air from the train pipe to pass through the supplemental valve casing and engage the end of the main valve 24 and to shift said valve to an open position wherein the discharge port 28 of the main valve casing is uncovered and the air pressure in the valve casing 23 and train pipe thus released. The supplemental valve casing 25 forms the core of a solenoid 36 which when energized draws the supplemental valve 26 inwardly thereby uncovering the discharge passage 34 and permitting the

air in the supplemental valve casing to escape through the passages 33 and to engage and operate the main valve in the manner described. The valve 26 is provided with a suitable stem 37 whereby the same may be manually reset after being actuated by the solenoid. The valve 22 forms the subject matter of the separate application Serial No. 740,245 filed January 4, 1913, and reference to this case should be had for a more particular description of the construction and operation of this valve.

The solenoid 36 of the valve 22 has connected thereto the current conducting wires 38 and 39 of an electric circuit arranged in the locomotive or car and which has therein a battery 40 by means of which the solenoid is energized. In the circuit containing the battery 40 are two relays in multiple one of which 41 is wound with very small wire making a high resistance, while the other relay 42 is wound with comparatively few coils of coarser wire, and thus has a very low resistance. The relation of the resistances of these two relays must be calculated with reference to the current and voltage of the battery 15 in the base of the semaphore and with reference to the resistance formed by the coil 19 in the current conducting wire 18 which connects said semaphore battery with the third rail of the system. In the current conducting wire 39 of the valve and battery circuit in the engine are arranged switches or circuit closers 43 and 44 which form respectively the armatures of the relays 41 and 42 and are operated by said relays to close the circuit when said relays are energized by the current from the semaphore battery which passes through the third rail and through the shoe 9 which is connected with the battery circuit through a branch wire 45 as shown.

Arranged in the current conducting wire 38 of the valve and battery circuit of the locomotive is a red light 46 which, when the valve is operated to release the air, is lighted, thus indicating to the engineer that the signal he has passed was set at danger and that the brakes are being automatically applied. Also connected with the current conducting wire 38 by branch wires 47 and 48 are orange and green lights 49 and 50 to which are respectively connected current conducting wires 51 and 52 the terminals of which are adapted to be engaged by the switch or circuit closer 43 of the relay 41 whereby when said switch or circuit closer is actuated by said relay the orange light 49 will cut into the circuit of the battery 40 thereby indicating to the engineer that the semaphore signal just passed indicated caution. When the relay 41 is deenergized or when the arms of the semaphore signal indicate safety the circuit closer or switch 43 will be in engagement with the contact termi-

nal of the current conducting wire 52 from the green light 50 thereby cutting said light into the battery circuit of the locomotive and indicating to the engineer that the track 5 is clear and that the semaphore signal indicates safety.

In the form and arrangement of the apparatus shown in Fig. 1 and described in the foregoing wherein the signals are repeated 10 or displayed in the cab of the locomotive and wherein the distant signal arm of the semaphore is shown at a position indicating caution and the local signal arm is in a position indicating safety the passage of the current 15 and the operation of the apparatus would be as follows: When the distant signal arm of the semaphore indicates caution as shown, the circuit closer or switch 21 in the base of the semaphore will be closed 20 while the switch 20 remains open as the home or local signal arm controlling this switch is at a position indicating safety. When the switch 21 is thus closed the current from the semaphore battery 15 is connected 25 with and energizes the third rail 6 but in doing so this current must pass through the resistance coil 19 in the current conducting wire 18. The current from the third rail 6 passes through the shoe 9 thence 30 through the current conducting wire 45, the branch circuit wires 53 and 54 of the relays 41 and 42, thence through the return wire 55 through the axle 4, wheels 5 track rail 1, and through the wire 16 which connects 35 said track rail with the semaphore battery 18 thereby completing the circuit to the relays. This current in passing from the current conducting wire to the relay circuit wires 53 and 54 passes through a pole 40 changer 56 the purpose of which will be hereinafter described. As hereinbefore stated the current in passing from the semaphore battery 15 and through the resistance coil 19 is reduced and when so reduced this 45 current has not strength enough to operate the relay 42 but does act upon the relay 41 thereby energizing the latter and causing the same to attract the armature switch or circuit closer 43 which when thus actuated, 50 is brought into contact with the terminal of the branch wire 51 leading to the orange light and thereby completing the circuit of the battery 40 through the light which will indicate to the engineer that the 55 signal just passed indicated caution. As the circuit closer or switch 43 of the relay 41 is not equipped with a spring it will be seen that the switch will remain in contact with the terminal of the 60 orange light wire 45 and will keep the circuit of this light closed and the light burning until the next signal is reached; if at the next station both of the semaphore arms are in safety position, the circuit of battery 15 65 will be broken and the third rail 6 thereby deenergized, thus permitting the current to flow from one terminal of battery 40 through conductor 45, to shoe 9, third rail 6, shoe 8, conductor 57 and relay 58 to the opposite pole of said battery. This current 70 energizes the magnet 58 and causes the same to attract armature 43 of relay 41 and so disengages the switch from the contact terminal of the orange light 51 and brings the same into engagement with the contact terminal of the green light 52 thereby cutting out said orange light and putting the green light into the circuit and indicating safety. The switch 43 will now remain in contact with the terminal of the green light, causing 80 the same to burn until a station is reached having either the caution or danger arm of the semaphore in horizontal position, if either of these are in position, third rail 6 will be brought into circuit with battery 15 85 energizing said rail, which will upon shoe 9 contacting therewith, operate as hereinbefore described. This stronger current of battery 15 will overcome the the weaker current flowing from battery 40 to the relay 58 90 as before described causing the releasement of armature 41 if either arm of the semaphore is in horizontal position.

In case the home or local signal arm 11 of the semaphore was set at danger the current from the semaphore battery 15 would travel through the switch 20 which would have been closed by the movement of the arm 11 to a danger position. From the switch 20 the current would pass through the wire 17 95 directly to the third rail 6 instead of through the resistance coil 19 so that the full force of the current from the batfery 15 is applied to the third rail and from thence passes to the apparatus in the locomotive. This current from the third rail 6 passes through the shoe 9 and current conducting wire 45 to the relay circuit wires 53 and 54 and having full strength the current would energize both of the relays 41 and 42. The relay 42 when 100 thus energized will attract its armature switch 44 thereby connecting the current conducting wire 59 from the valve 22 and completing the circuit through the battery 40, wire 58, red light 46, and valve 22 thereby 105 energizing the solenoid of said valve and causing the latter to open and release the air pressure in the train pipe thus applying the brakes. The passage of the current through the red light 46 lights the latter which will 110 indicate to the engineer in the cab that the signal just passed was set at danger and that the brakes are being automatically applied. If desired an electric bell or other alarm 115 (not shown) may be placed in the circuit of the red light and sounded when a current is sent through this circuit, thus providing an audible signal for attracting the attention of the engineer.

From the foregoing it will be seen that 120

during the time shoe 9 is in contact with a ramp rail having therein the proper form and strength of current, relay 42 will be energized and its armature elevated so as to close the circuit of the danger signal and solenoid valve, operating the same to release the air and apply the brakes. In this connection, however, it is to be noted that the ramp rail must be of such length (about 1000 feet 10 more or less) so as to retain the circuit of the solenoid valve in the closed condition until the latter has had sufficient time to act as hereinbefore stated. As both the relays 41 and 42 are energized when the semaphore 15 signal indicates danger both the red and orange lights in the cab would burn and in order to extinguish the orange light, I preferably provide a circuit breaker or switch 59 comprising an electro-magnet 60 arranged 20 in the red light circuit and adapted to be energized by the current passing therethrough and which has its armature forming the movable member 61 of the switch, said member being arranged in the orange light 25 circuit 51 whereby when the magnet 60 is energized the armature switch member 61 will be attracted by the magnet and the orange light circuit thus broken leaving only the red light burning as will be readily understood.³⁰

When the form and arrangement of the apparatus described in the foregoing is employed on a signal track system there would be arranged on the opposite side of the track 35 from the semaphore 10 a similar semaphore, (not shown in the drawings) but which would be connected with the third rail by a current conducting wire 62 arranged and connected with the operating mechanism in 40 the semaphore in exactly the same manner as shown and described in connection with the semaphore 10. In this arrangement however, the third rail would be separated by electrical insulation or as shown in the 45 drawings would be divided into two sections 6 and 7 and the connection 62 would be made with the right hand section 7 as shown. In this arrangement it is also necessary that the two sections 6 and 7 of the third rail 50 shall be of opposite polarity and that the relay circuit be provided with the pole changer 56 hereinbefore referred to. In this arrangement the relays 41 and 42 are not polarized but instead a reverse current relay 55 63 is connected in parallel in the circuit of relay 42. This reverse current or polarized relay has its armature acting as a bridge of a break in conductor 53, one end of said break being connected to the contact 53' and 60 the other to the armature of relay 63. By this arrangement the armature of relay 63 which normally is out of engagement with the contact 53', may be brought into contact with the latter to close the break and complete the circuit to relay 42 when the contact

shoe engages a rail section 6 charged with a negative form of current, but will be unaffected by the rails charged with a positive current, and vice versa, so that if it is desired that the relays 41 and 42 should be energized 70 only by a positive current, then when the contact shoe engages a rail carrying a negative current, the circuits of two relays 41 and 42 will be broken and consequently their armatures will be unaffected. When the 75 train is traveling in the opposite direction from that indicated in the drawings the pole changer is thrown to the position indicated by the dotted lines in Fig. 1 of the drawings in which position the relay 63 80 opens or breaks the relay circuit when the third rail is negative but closes the circuit when the third rail is positive as will be readily understood.⁸⁵

From the foregoing it will be seen that the position of the signal and the condition of the track at the entrance of each block is indicated in the cab of the locomotive or motor car and that the signal in the locomotive or car remains at this position until 90 the train enters a block having a different signal whereupon the change in the signals will be immediately indicated in the locomotive or car.⁹⁵

The contact shoes shown and described in the various forms of the apparatus may be of any suitable construction one form thereof being illustrated in Fig. 4 of the drawing as consisting of a block, the lower corners of the ends of which are rounded 100 to facilitate the engagement thereof with the third rail. The shoe is preferably loosely connected with the locomotive or motor car by links 105 the lower ends of which are pivotally connected with the shoe 105 while the upper portions thereof have a sliding engagement with stud bolts or the like 106 secured to a suitable part of the frame or running gear of the locomotive. The third rails shown and described in the 110 various forms of the apparatus may also be of any suitable construction and are preferably formed from old or worn sections of track rails. The length of the third rails would be gaged by the speed of the 115 train but for the fast running trains, need not be more than two or three lengths of track rails.¹²⁰

Having thus described my invention, what I claim is:

1. In a brake setting apparatus, the combination with a track signal, of a contact rail controlled by said track signal and energized when the latter is in operative position, a relay circuit carried by the train, a contact shoe, the latter having an electrical connection with said relay circuit, a relay included in said circuit, a battery circuit carried by the train, an electrically operated valve included therein, a switch 125

- arranged in said battery circuit and controlled by said relay whereby to open and close said circuit and coöperating means included in said relay circuit to control the latter whereby said relay may be unaffected by a negative and energized by a positive current or energized by a negative current and unaffected by a positive one.
2. In a brake setting apparatus, the combination with a track signal, of a contact rail controlled by said track signal and energized when the latter is in operative position, a relay circuit carried by the train, a contact shoe, the latter having an electrical connection with said circuit, high and low resistant relays included in the latter, a battery circuit, an electrically operated valve included therein, a danger signal arranged in said circuit, a switch included in said battery circuit, and controlled by said high resistance relay to open and close said circuit, branch circuits connected to said battery circuit, caution and safety signals included therein, a switch controlling said branch circuits and influenced by said low resistance relay, and coöperating means included in the circuit of said relays and controlling the latter whereby they will be energized by a positive and unaffected by a negative current or energized by a negative and unaffected by a positive one.
3. In an electrical brake setting apparatus, the combination with a track signal, of a contact rail controlled by said track signal and energized when the latter is in operative position, a relay circuit carried by the train, a contact shoe, the latter having an electrical connection with said circuit, high and low resistant relays included in the latter, a battery circuit, an electrically operated valve included therein, a danger signal arranged in said circuit, a switch included in said battery circuit, and controlled by said high resistance relay to open and close said circuit, branch circuits connected to said battery circuit, caution and safety signals included therein, a switch controlling said branch circuits and influenced by said low resistance relay, and coöperating means included in the circuit of said relays and controlling the latter whereby they will be energized by a positive and unaffected by a negative current or energized by a negative and unaffected by a positive one.
4. In an electrical brake setting apparatus, the combination with a track signal, of a contact rail controlled by said track signal and energized when the latter is in operative position, a relay circuit carried by the train, a contact shoe, the latter having an electrical connection with said circuit, high and low resistant relays included in the latter, a battery circuit, an electrically operated valve included therein, a danger signal arranged in said circuit, a switch included in said battery circuit, and controlled by said high resistance relay to open and close said circuit, branch circuits connected to said battery circuit, caution and safety signals included therein, a switch controlling said branch circuits and influenced by said low resistance relay, and coöperating means included in the circuit of said relays and controlling the latter whereby they will be energized by a positive and unaffected by a negative current or energized by a negative and unaffected by a positive one.

In testimony whereof I have hereunto set my hand in presence of two subscribing witnesses.

THOMAS H. SHELDON.
